ABSTRACT OF THE DISCLOSURE

This invention provides an apparatus for feeding a fabric web onto a tentering frame of a tentering machine. The apparatus includes a means connecting an electrical control circuit to at least one oil engine means for adjusting the speed and direction of movement of the feed bars on a tentering frame. A feeler lever having a fabric edge tracing portion and a control circuit activating portion is pivotally mounted to activate a switch mechanism within said control circuit. The electrical control circuit includes means to control the current intensity provided by the said control circuit to a moving coil regulator. The moving coil regulator is connected to an oil engine for regulating the amount of oil to adjust the feed bars at a speed proportional to the amount of forward movement of the fabric web edge. The control circuit activating portion of the feeler lever is movable to various positions within the control circuit. The current intensity control means operates directionally with respect to the movement of the feeler lever activating portion within the said control circuit in response to the movement of said fabric edge tracing portion which is in contact with the fabric web edge moving into the tentering machine.

BACKGROUND OF THE INVENTION

This invention relates to entering arrangements for fabric tentering machines, and more specifically to an equipment in which feed bars of a tentering frame are controllable by means of a feeler switch in dependence on the course of the edge of a web of fabric to be introduced.

From German Patent No. 683,413 an entering arrangement of this type has already become known in which rapid forward movement of the edges of the fabric is effected with a high adjusting speed and slow forward movement with a correspondingly low adjusting speed.

In this known arrangement an adjusting motor was controlled by means of a pivotable feeler switch influencing the intensity and direction of current in an electric control circuit in dependence on its position, in such a manner that it caused adjustment of the feed bars of the tentering frame in a direction corresponding to the course of the edge of the web of fabric to be introduced and at a speed proportional to the amount of forward movement.

Hitherto adjusting motors electric motors have been used, the reaction velocity of which did not meet the requirements without further frequently very expensive expedients requiring additional attendance.

SUMMARY OF THE INVENTION

The present invention provides an entering arrangement for fabric tentering machines which comprises a pivotable feeler switch, an electric control circuit, said feeler

2

switch influencing the current intensity in said electric control circuit in dependence on its position, an adjusting motor controllable by means of said feeler switch in such a manner that it causes adjustment of feed bars on the tentering frame of the fabric tentering machine in a direction corresponding to the course of the edge of a web of fabric and at a speed proportional to the amount of forward movement of the edge of said web, a moving-coil regulator having its coil arranged in said control circuit influenced by said feeler switch, and at least one oil engine serving as adjusting motor, said moving-coil regulator being arranged to regulate the amount of oil of said oil engine.

This construction has the advantage that nearly inertialess control members co-operate with low-inertia servomotors, whereby an extremely rapid adaptation of the position of the feed bars to the course of the edge of the web of fabric is achieved even in the event of a rapid change of the course.

In this arrangement the feeler switch includes a feeler which is constructed in a known manner as a two-armed lever and which may constitute with one of its arms a movable core of a set of induction coils or may be connected with a displaceable core of a differential transformer, the output voltage of which set of induction coils or differential transformer is preferably transmitted via an amplifier to the control circuit containing the moving-coil regulator.

However, the feeler switch may also connect as a multiple-contact switch via appropriate resistors control circuits of different voltages directly to the moving-coil regulator without an amplifier. In this construction, if desired, an adjustment of the sensitivity of response of the entering arrangement may be effected in a simple manner.

As a device acting directly on the feed bar of the tentering frame, use is preferably made of a member which is connected to the feed bar and which may be, for example, in the form of an adjusting nut screwed on a spindle driven by the adjusting motor or in the form of a lug or projection movable by a band which may be endless if desired, a chain or the like driven by the adjusting motor or in the form of a similar device.

BRIEF DESCRIPTION OF DRAWINGS

Several embodiments of the invention will now be described by way of example and with reference to the accompanying drawings, in which:

FIG. 1 is a schematic side elevational view of an entering arrangement according to the invention;

FIG. 2 is a front elevational view of an entering arrangement with spindle adjustment;

FIG. 3 is a similar view of an entering arrangement with band adjustment;

FIG. 4 is a diagram showing the feeler switch with a set of induction coils;

FIG. 5 is a diagram showing the feeler switch with a differential transformer;

FIG. 6 is a diagram showing the feeler switch constructed as a multiple-contact switch, and

FIG. 7 is a diagram showing the feeler switch constructed as a multiple-contact switch and having an adjustable strip carrying the contacts.

DESCRIPTION OF SPECIFIC EMBODIMENTS

With reference now to the drawings and particularly to FIGS. 1 to 3, a web of fabric B is arranged to be fed into an entering arrangement as proposed by the invention by means of a guide roller 1 mounted in a feed frame 2 and is to be fixed with pins on each side to a

feed chain 3 adapted to run in a rail which is fixed to a feed bar 4 ahead of a first drying chamber 5.

Mounted on the feed bar 4 is a feeler switch F which by means of an arm 6 of a feeler constructed as a two-armed lever serves to trace the edge of the fabric prior to its entering the region of the rail in which the feed chain 3 is guided.

This feeler switch F may be constructed so that the feeler, e.g. in the embodiment shown in FIG. 4, is arranged to co-operate with a pair of induction coils 8 in that an arm 7 of the feeler in the form of a metallic lug is swung more or less into the coil system in accordance with the deflection of the tracing arm 6 and varies the self-induction accordingly. In the embodiment shown in FIG. 5 the feeler is arranged to co-operate with a differential transformer 9 in that the arm 7 of the feeler shifts a steel pin in the windings of the transformer.

The different output voltages occurring in both embodiments are supplied via an amplifier V to a control circuit 10 in which the coil of a moving-coil regulator T is arranged. This regulator consists in a known manner of an axially movable coil which is excited by the control circuit and carries along during its movements a control valve serving to control the amount of oil fed from a pump P to an oil engine M.

The oil engine in this case serves as an adjusting motor and drives an adjusting member VG arranged directly to adjust the feed bar.

This adjusting member may consist, for example, of a driven spindle 11 on which a nut 12 fixed to the feed bar 4 is screwed, as shown in FIG. 2, or of a driven endless band, chain or the like 13 which is arranged to take along a lug or similar projection 14 secured to the feed bar (see FIG. 3), or of a similar device.

FIG. 6 shows an embodiment wherein the feeler of the feeler switch F is arranged with its arm 7 in the control circuit and at contacts 15 connects control circuits 10' with two different voltages via appropriate resistors not shown to the moving-coil regulator T, in this case the inner contacts supplying a voltage for a lower adjusting speed and the outer contacts a voltage for a higher adjusting speed in both directions. In all other respects the equipment corresponds to that shown in FIGS. 4 and 5.

FIG. 7 shows a feeler switch F with contacts for three velocity stages, wherein three contacts are provided for each of the two directions of rotation of the engine M in the form of elongated small metal plates 15' lying side by side at short distances apart and directed toward the pivot of the feeler formed of the arms 6 and 7.

These small contact plates are positioned on both sides of a small trapezoidal no-load plate 16 of the same thickness which corresponds to the central switch-off position of the feeler. All seven small plates are arranged on a strip 17 which is adjustable to a certain extent along a guide 18 in the longitudinal direction of the feeler situated in its central position. The adjustment can be effected through an eccentric 20 and a pull rod 21 by operating a turning knob 19. As can be seen from FIG. 7, by shifting the strip 17 carrying the contacts from the upper position shown in full lines in the direction toward the lower position shown in dot-and-dash lines, the path of movement of a contact 22 of the feeler from its central position to the left-hand or right-hand innermost contact is extended and thus the sensitivity of response of the switch reduced and vice versa.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description and all changes which come within the meaning and range of equivalency of the claims are therefore intended to be embraced therein. For example, still other forms of construction of the feeler switch are imaginable. In

stead of a unilaterally driven endless band or chain for adjusting the feed bar a plain band or the like driven alternately at its two ends may be provided.

We claim:

- 5 1. An apparatus for feeding a fabric web onto a tentering frame of a tentering machine, comprising in combination,
  - (a) means connecting an electrical control circuit to at least one oil engine means for adjusting the speed and direction of movement of feed bars mounted on the tentering frame,
  - (b) means pivotally mounting a feeler lever having a fabric edge tracing portion and a control circuit activating portion within a switch mechanism,
  - (c) said electrical control circuit includes means to control the current intensity provided by said control circuit to a moving coil regulator, and
  - (d) means connecting said moving coil regulator to said oil engine means to regulate the amount of oil in said engine for adjusting the feed bars at a speed proportional to the amount of forward movement of the fabric web edge,
  - (e) said control circuit activating portion being movable to various positions in said control circuit switch mechanism to cause the current intensity control means to operate directionally with respect to said various positions in response to the movement of said fabric web edge tracing portion along said fabric web edge.
- 10 2. An apparatus as defined in claim 1 wherein said current intensity control means includes a set of induction coils and said control circuit activating portion includes the coil of said set of induction coils.
- 15 3. An apparatus as defined in claim 2 wherein said control circuit includes an amplifier means to transmit output voltages of said set of induction coils to said moving coil regulator.
- 20 4. An apparatus as defined in claim 1 wherein said current intensity control means includes a differential transformer and said control circuit activating portion includes a displaceable core for said differential transformer.
- 25 5. An apparatus as defined in claim 4 wherein said control circuit includes an amplifier means to transmit output voltages of said differential transformer to said moving coil regulator.
- 30 6. An apparatus as defined in claim 1 wherein said control circuit includes a switch means having a plurality of contacts and resistor means connecting each contact to said moving coil regulator, and said control circuit activating portion of said feeler lever pivotally touches said contacts in response to movement of the fabric edge tracing portion of said feeler lever.
- 35 7. An apparatus as defined in claim 6 wherein said contacts are elongated small metal plates directed toward the pivot of the feeler at short distances apart on both sides of a small no-load plate which increases in width in the form of a trapezoid in a direction away from the pivot of the feeler, and said switch means include means mounting said plates onto an adjustable strip and means for guiding said adjustable strip in the longitudinal direction of the feeler lever when said lever is in a central position.
- 40 8. An apparatus as defined in claim 6 wherein said switch means include a guiding means having means operably connecting a knob and an eccentric to said strip to adjust the location of said contacts.
- 45 9. An apparatus as defined in claim 1 wherein said feed bar adjusting means includes a spindle having a nut screwed thereon and further including a means for directly driving said spindle by said oil engine.
- 50 10. An apparatus as defined in claim 1 wherein said feed bar adjusting means includes a means for

- directly driving an endless band by said oil engine.
11. An apparatus as defined in claim 1 wherein said feed bar adjusting means includes a means for directly driving an endless chain by said oil engine.
12. An apparatus as defined in claim 1 wherein said feed bar adjusting means includes two oil engines which are each operable in its own direction of rotation and a means for alternately driving an endless band by each of said two oil engines.
13. An apparatus as defined in claim 1 wherein said feed bar adjusting means includes two oil engines which are each operable in its own direction of rotation and a means for alternately driving an endless chain alternately by said oil engines.
